DESIGN FOR A TRANSFORMER CABINET

Arthur Charles Haggstrom, Rockford, Ill.

Application April 27, 1937, Serial No. 68,994

Term of patent 7 years

To all whom it may concern:

Be it known that I, Arthur Charles Haggstrom, a citizen of the United States, residing at Rockford, in the county of Winnabago, in the State of Illinois, have invented a new, original, and ornamental Design for a Transformer Cabinet of which the following is a specification, reference being had to the accompanying drawing, forming part thereof.

Fig. 1 is a perspective view of a transformer cabinet showing my new design.

Fig. 2 is a view of either end thereof.

Fig. 3 is a fragmental section with parts in elevation and parts in section of the end of the cabinet taken at line 3—3 of Fig. 2.

I claim:

The ornamental design for a transformer cabinet as shown.

ARTHUR CHARLES HAGGSTROM.
